CONVERSION OF HYDROCARBONS

Harold R. Legatski, Bartlesville, Okla., assignor
to Phillips Petroleum Company, a corporation
of Delaware

Application November 5, 1945, Serial No. 626,867

3 Claims. (Cl. 260—666)

1

This invention relates to the conversion of hydrocarbons. In one aspect this invention relates to isomerization of saturated normal paraffins and saturated mono-cycloparaffins. In a more particular aspect this invention relates to the isomerization of normal hexane and methylcyclopentane. In another aspect this invention relates to the preparation of a feed composition for an isomerization process.

Natural and straight run gasolines are usually separated into their various components by fractional distillation and the components thus separated are utilized in various ways. Generally, natural and straight run gasolines are separated into about seven fractions. The lightest fraction comprises propane and lighter hydrocarbons. This fraction is further separated into propane which is marketed commercially as liquefied petroleum gas. The lighter hydrocarbons from this fraction may be used in the production of carbon black. The second fraction is a butane fraction comprising isobutane and normal butane. The two butanes are separated and the isobutane is usually alkylated with butylene to form octanes. The normal butane is marketed as liquefied petroleum gas, or may comprise a feed for the manufacture of butadiene, or may be used as a gasoline blending agent. A pentane fraction is also separated from the natural gasoline containing isopentane and normal pentane. The isopentane is a blending ingredient for both aviation and high octane motor fuels. Normal pentane is used as a solvent and as blending agent for motor fuels. A fourth fraction comprising isohexane and normal hexane is separated and the isohexane fraction is used in both aviation and motor fuels for increasing the octane quality of the product. The normal hexane fraction, which usually contains a large proportion of methylcyclopentane, is used in motor fuels and as a solvent. An isoheptane fraction separated from the natural or straight run gasoline is used as a component of 100 octane gasoline. Still another fraction separated from the natural and straight run gasoline is composed of normal heptane and isoctane. This fraction is further separated into its components. The normal heptane has various uses, such as a solvent and as a feed for the manufacture of toluene. Isooctane is used as aviation fuel base stock and in high octane motor fuel. Usually the last fraction from the separation of the natural and straight run gasoline comprises normal octane and heavier hydrocarbons which are used as a reforming feed stock.

2

The hexane fraction separated from the natural gasoline and straight run gasolines is of particular interest since the isohexanes have been found to be a valuable blending ingredient in super aviation fuels. Because of the more or less inability to isomerize both the normal hexane and the methylcyclopentane together to obtain a good yield of both cyclohexane and isohexanes simultaneously, this fraction has been used directly as a solvent or as a motor fuel blending agent without further treatment. It is highly desirable to provide a method for isomerizing both normal hexane and methylcyclopentane simultaneously to isohexane and cyclohexane, respectively, especially since cyclohexane is a valuable starting material for the production of numerous organic chemicals.

The object of this invention is to isomerize saturated normal paraffins and saturated mono-cycloparaffins.

It is an object of this invention to provide a method for isomerization of a normal hexane-methylcyclopentane fraction.

It is another object of this invention to provide a novel isomerization process for the production of a high quality hexane fraction as a motor fuel blending agent.

Still another object of this invention is to provide a feed composition for efficient isomerization of a hexane fraction.

Other objects and advantages of the present invention will become apparent to those skilled in the art from the accompanying description and disclosure.

Unexpectedly, it has been found that a hydrocarbon fraction comprising an admixture of saturated normal paraffins and saturated mono-cycloparaffins can be isomerized in a manner hereinafter described to produce an exceptionally high yield of isomeric products which may be used in admixture as a blending agent for high quality motor fuels. By separating the aforesaid hydrocarbon fraction into a normal paraffin concentrate and a cycloparaffin concentrate, and separately isomerizing the respective concentrates, the effluents of which are recombined, a higher quality fraction can be obtained than possible by a single isomerization of the original hydrocarbon fraction.

The drawing diagrammatically illustrates a flow of materials for the separation of the various fractions from natural and straight run gasoline, and the isomerization of a hexane fraction according to this invention. The drawing is self-explanatory.

According to this invention, a hexane fraction obtained from a fractionation of natural or straight run gasolines boiling within the range of about 150 to about 160° F. and comprising normal hexane and methylcyclopentane is separated into two fractions. A typical normal hexane fraction as above comprises about 70 weight per cent normal hexane, about 25 weight per cent methylcyclopentane, and about 5 weight per cent isohexanes. Generally, the composition of a hexane fraction to which the present invention is applicable is between about 65 and about 80 weight per cent normal hexane and between about 35 and about 20 weight per cent methylcyclopentane. The normal hexane fraction is separated into a normal hexane concentrate and a cycloparaffin concentrate by conventional fractional distillation. Preferably, the normal hexane concentrate contains at least about 85 weight per cent and up to about 93 weight per cent normal hexane and the cycloparaffin concentrate contains at least about 40 weight per cent methylcyclopentane. Each concentrate or fraction is then isomerized under appropriate conditions to obtain the desired isomeric product. In the case of the normal hexane concentrate, the isomerization product is isohexane; in the case of the methylcyclopentane concentrate, the isomerization product is cyclohexane. In isomerizing the normal hexane concentrate it has been found that at least 7 to about 12 weight per cent or more methylcyclopentane is desirable to inhibit side reactions, such as disproportionation, dealkylation and cracking. By separately isomerizing a concentrated normal hexane fraction and a concentrated methylcyclopentane fraction the yield of isohexane and cyclohexane is greatly increased.

The normal hexane isomerization effluent generally contains more than about 55 weight per cent isohexanes and less than about 10 weight per cent cycloparaffins. The methylcyclopentane isomerization effluent generally contains more than about 25 weight per cent cyclohexane.

Isohexane is recovered from the normal hexane isomerization effluent as a product of the process and cyclohexane is recovered from the methylcyclopentane isomerization effluent also as a product of the process. If desired these components, isohexane and cyclohexane, or the entire effluents from the respective isomerizations, may be combined to form a motor fuel blending agent. Unconverted methylcyclopentane and normal hexane from the isomerization effluents may be recycled as a portion of the feed to the respective isomerization processes. A portion of the unconverted methylcyclopentane may be added to the feed to the normal hexane isomerization in order to maintain the naphthenic content of the feed within the desired limits.

This invention is equally applicable to the isomerization of other mixtures of saturated normal paraffins and saturated mono-cyclohydrocarbons as herein described. For example, a normal heptane fraction containing an appreciable amount of methylcyclohexane is fractionated to form a normal heptane concentrate and a methylcyclohexane concentrate. The normal heptane concentrate is isomerized under optimum reaction conditions to produce isoheptanes, and the methylcyclohexane is isomerized under optimum reaction conditions to produce dimethylcyclopentane. Both products of the separate isomerization reactions are excellent blending agents for motor fuels, thus the products are combined

as a single blending agent. By separate isomerization of the normal heptane concentrate and the methylcyclohexane concentrate ultimately a higher quality blending agent can be obtained by combining the products of the separate isomerization reactions than could be obtained by a single isomerization of the original mixture.

The isomerization of the hexanes is carried out under appropriate conditions of temperature, pressure and residence time known in the art.

10 A preferred catalyst comprises a Friedel-Crafts metal halide in the form of a hydrocarbon complex or supported on suitable inorganic material. The isomerization of either the normal hexane 15 concentrate or the methylcyclopentane concentrate may be carried out in either the liquid or vapor phase without departing from the scope of this invention. Liquid phase isomerization is preferred.

20 Among the solid inorganic catalyst supports suitable in vapor phase isomerization are the mineral or mineral-like compounds, preferably nearly completely dehydrated, such as the kaolinites, Terrana, Floridin, pyrophyllite, apophyllite, 25 meerschaum, serpentine, kieserite, bentonite, talc, bauxite, the permutites, the zeolites and the like, as well as the prepared hydrated materials such as the prepared permutites and zeolites, aluminum oxides, magnesium oxides, silica, and similar compounds prepared by partial dehydration 30 of the hydroxides and the like.

The above materials are employed in admixture or in combination with an active metal halide isomerization catalyst of the Friedel-Crafts or aluminum halide type. Preferred catalysts are those comprising aluminum chloride and aluminum bromide.

35 The catalytic material in any suitable solid form as powder, pillules, pellets, or granules of the 40 desired size is employed in manners customary in the execution of catalytic processes of this type. The desired quantity of the granular catalyst material may be packed or otherwise contained in a reaction tube, chamber or tower and maintained at the desired temperature by suitable heating and/or cooling means while the material to be treated is passed into contact with it under the appropriate pressure for the required 45 period of time.

50 Vapor phase isomerization, generally, is executed at a temperature not greater than about 450° F. and preferably at temperatures below 325° F. At temperatures above 450° F. losses of material due to undesirable cracking reactions 55 are prohibitive. The lower limit of temperature range is set by that temperature at which the desired isomerization will take place at a practical rate. Temperatures as low as about 200° F. may be used in some cases where pressure is low 60 enough to assure vapor phase operation. A preferred practical operating range is from about 200 to about 325° F.

65 Unless fairly high pressures are used, the catalyst may suffer loss of activity because of the sublimation of the metal halide therefrom. Thus, it is preferred to use pressures from about 100 to about 400 pounds per square inch gage. In practice the temperature and pressure are adjusted so that the isomerization reaction is carried out in the vapor phase. If the reaction is 70 effected under moderately superatmospheric pressures of from about 25 to about 350 pounds per square inch gage, practicable conversion of the hexanes to the desired isomeric products can 75 be effected at relatively lower temperatures than

when the process is executed at atmospheric or lower pressures.

The presence in the reaction system in vapor phase isomerization of a hydrogen halide or substance capable of yielding a hydrogen halide under the conditions existing in the reaction system appears to have a beneficial effect upon the life and activity of the metal halide-containing catalyst, particularly those containing an aluminum halide. In many cases it is beneficial to the reaction to have relatively small amounts of hydrogen chloride added to the reactants and present during the reaction. As a substance capable of yielding a hydrogen halide, tertiary butyl chloride and the like halides which will decompose under reaction conditions to yield the hydrogen halide, may be added to the system. The amount of hydrogen halide within the reaction zone at any time should not be more than 10 mol per cent for best results.

The most suitable contact time will depend upon the particular catalyst, upon the reaction conditions, and upon the feed used. The contact time is chosen so that a practicable conversion is obtained with the minimum side reactions. In isomerization of hexanes in the vapor phase at temperatures between 200 and 325° F., contact times from about 1 to about 20 minutes are used.

The catalyst in vapor phase isomerization, after it has suffered substantial deactivation because of use in the process, can be restored to its initial activity by addition of an aluminum halide. The reactivation can be effected without removing the catalyst from the reaction chamber, while the catalyst is functioning, but preferably after the catalyst has temporarily been taken out of use.

The catalyst employed in liquid phase isomerization comprises essentially a Friedel-Crafts metal halide which will form a sludge complex with an olefinic polymer, kerosene, or an alkylate. This hydrocarbon-metal halide complex having some free metal halide therein is a very active catalyst. The spent sludge may be withdrawn from the reaction chamber and disposed of since it is relatively cheap, or it may be regenerated for reuse.

The presence in the reaction system during liquid phase isomerization of a hydrogen halide appears to have a beneficial effect upon the life and activity of the catalyst. It is, therefore, beneficial to the reaction to have relatively small amounts of hydrogen chloride added to the reactants and present during the reaction.

The pressure of the reaction chamber in liquid phase isomerization is maintained so as to keep the hexanes in the liquid phase in the chamber at the isomerization temperatures. Preferred pressures are from about 200 to about 450 pounds per square inch gage. The reaction temperatures for liquid phase isomerization are somewhat lower than those temperatures used in vapor phase isomerization. The reaction temperatures may range from about 100 to about 375° F., and preferably from about 150 to about 275° F.

The contact time of the feed with the catalyst for liquid phase isomerization may vary within a relatively large range without affecting the conversion process. Contact times from about 2 to about 30 minutes are most desirable.

The reaction chamber for liquid phase isomerization may be packed with a solid catalyst supporting material or carrier agent, such as carbon Raschig rings, of such a nature as to

have a high wettability by the catalyst sludge. The high wettability of the supporting material assures a large hold-up of the catalyst sludge. This packing material is ordinarily relatively inert with respect to reactants and catalyst. Examples are Raschig rings, Berl saddles, etc., made from carbon, glazed or unglazed porcelain or other ceramic wear. Other types of packing which may be used include bauxite, activated alumina, fuller's earth, silica gel which may have adsorptive properties enhancing the activity of the sludge catalyst. The reaction for liquid isomerization may contain no supporting material at all, but instead intimate contact between reactants and catalyst is effected by means of stirrers within the reaction chamber itself.

Various other isomerization catalysts may be used which are suitable for isomerization of hexanes, such as hydrogen fluoride, boron trifluoride, mixtures of hydrogen fluoride and boron trifluoride, and sulfuric acid. Reaction conditions of isomerization and the catalyst used for the various isomerization steps may be altered and various modifications will become apparent to those skilled in the art without departing from the scope of this invention.

Preferably, the normal hexane concentrate is isomerized at a temperature between about 210 and about 375° F. and under sufficient pressure to maintain the reaction mixture in the liquid phase. An aluminum chloride-hydrocarbon complex containing between about 50 and about 80 weight per cent aluminum chloride is preferred as the catalyst. The methylcyclopentane concentrate is isomerized at a temperature between about 100 and 200° F. under sufficient pressure to maintain the reaction mixture substantially in the liquid phase. An aluminum chloride-hydrocarbon complex containing between about 10 and about 45 weight per cent aluminum chloride is preferred as the isomerization catalyst.

The following examples illustrate the increased yield of isohexane and cyclohexane according to this invention. The desirability of a minimum naphthenic content for the isomerization of normal hexane is also adequately shown in the examples to be described more fully hereinafter.

In the following examples the hydrocarbon feed was isomerized in the liquid phase in the presence of aluminum chloride under optimum conditions for the particular desired product.

EXAMPLE I

A normal hexane fraction was isomerized without preliminary fractionation. The following is the approximate feed and effluent compositions.

	Feed Composition, Weight Per Cent	Effluent Composition, Weight Per Cent
65 Pentanes and lighter		4.8
Isohexanes	5	52.9
Methylcyclopentane	21	9.8
Cyclohexane	4	7.2
Normal Hexane	70	19.2
Heavier hydrocarbons		6.1
	100	100.0

Normal hexane conversion = 72.4%

Isohexane yield per normal hexane reacted = 94.1%

Methylcyclopentane reacted = 53.8%

Cyclohexane yield per methylcyclopentane reacted = 29.8%

EXAMPLE II

A normal hexane concentrate was prepared by preliminary fractionation according to this invention and isomerized under optimum reaction conditions for the formation of isohexanes. The following is the approximate feed and effluent compositions.

Feed Composition, Weight Per Cent	Effluent Composition, Weight Per Cent
Pentanes and lighter	3.8
Isohexanes	55.1
Normal hexane	26.3
Methylcyclopentane	12.1
Cyclohexane	2.2
Heavier hydrocarbons	3.0
	9.6
	100.0
	100.0

Normal hexane reacted=70.1%
Isohexane yield per normal hexane reacted=89.5%
Methylcyclopentane reacted=81.9%
Cyclohexane per methylcyclopentane reacted=31%

EXAMPLE III

A methylcyclopentane concentrate was prepared by preliminary fractionation according to this invention and isomerized under optimum reaction conditions for the formation of cyclohexane. The following is the approximate feed and effluent compositions.

Feed Composition, Weight Per Cent	Effluent Composition, Weight Per Cent
Isohexane	6.0
Normal hexane	47.8
Methylcyclopentane	44.3
Cyclohexane	7.9
Heavier hydrocarbons	21.7
	27.2
	3.0
	100.0
	100.0

Normal hexane reacted=11.9%
Isohexane yield per normal hexane reacted=95%
Methylcyclopentane reacted=51.1%
Cyclohexane yield per methylcyclopentane reacted=85.4%

The 85 per cent yield of cyclohexane in Example III as compared to a 29 per cent and 31 per cent yield in Examples I and II, respectively, indicates the desirability of concentrating methylcyclopentane in a hydrocarbon fraction to at least about 40 per cent of the fraction.

EXAMPLE IV

Normal hexane substantially free from other hydrocarbons was isomerized under optimum reaction conditions, and the following composition of the effluent was obtained.

Composition of effluent weight per cent

Isobutane	15.3
Isooctane	14.9
Normal pentane	1.7
Neohexane	4.1
Other isohexanes	13.1
Normal hexane	37.3
Heptanes and heavier	13.6
	100.0

Conversion normal hexane=62.7%
Isohexane yield per normal hexane reacted=27.4%

Since the highest yield of isohexanes was obtained when methylcyclopentane was present in substantial amount in the reaction mixture, it is evident that a methylcyclopentane content of the isomerization feed above about 12 weight per cent is highly desirable to obtain a good yield of

5 isohexanes. Example IV adequately illustrates the

degree of disproportionation resulting when relatively pure normal hexane is isomerized without the presence of a disproportionation inhibitor, such as methylcyclopentane or other naphthene.

I claim:

1. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture 20 in the liquid phase and in the presence of an aluminum chloride-hydrocarbon complex containing between about 50 and about 80 weight per cent aluminum chloride, fractionally distilling an effluent from said normal hexane isomerization to 25 separate isohexane and normal hexane, recycling said normal hexane to the aforesaid isomerization, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, fractionally distilling an effluent 30 from said methylcyclopentane isomerization to separate cyclohexane and methylcyclopentane, recycling a portion of said methylcyclopentane to said methylcyclopentane isomerization, introducing another portion of said methylcyclopentane 35 into said normal hexane concentrate in an amount sufficient to maintain a naphthenic content therein of at least 7 weight per cent, and combining said isohexane and said cyclohexane as a motor fuel blending agent.
- 40 2. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 45 3. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 50 4. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 55 5. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 60 6. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 65 7. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.
- 70 8. A process for isomerizing a hexane fraction comprising between about 65 and about 80 weight per cent normal hexane and between about 20 and about 35 weight per cent methylcyclopentane which comprises fractionally distilling said hexane fraction to form a normal hexane concentrate comprising between about 85 and about 93 weight per cent normal hexane and a methylcyclopentane concentrate containing at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, and combining effluents from said respective isomerizations.

tilling said hexane fraction to form a normal hexane concentrate comprising between about 85 and about 93 weight per cent normal hexane and a methylcyclopentane concentrate comprising at least about 40 weight per cent methylcyclopentane, isomerizing said normal hexane concentrate at a temperature between about 210 and about 375° F. under sufficient pressure to maintain the reaction mixture in the liquid phase, and in the presence of an aluminum chloride-hydrocarbon complex containing between about 50 and about 80 weight per cent aluminum chloride, fractionally distilling an effluent from said normal hexane isomerization to separate isohexane and normal hexane, recycling said normal hexane to the aforesaid isomerization, simultaneously isomerizing said methylcyclopentane concentrate at a temperature between about 100 and about 200° F. under sufficient pressure to maintain the reaction mixture in the liquid phase and in the presence of an aluminum chloride-hydrocarbon complex containing between about 10 and about 45 weight per cent aluminum chloride, fractionally distilling an effluent from said methylcyclopentane isomerization to separate cyclohexane

10

and methylcyclopentane, recycling a portion of said methylcyclopentane to said methylcyclopentane isomerization, introducing another portion of said methylcyclopentane into said normal hexane concentrate in an amount sufficient to maintain a naphthenic content therein of at least 7 weight per cent, and recovering isohexane and cyclohexane from the respective isomerization effluents as products of the process.
